(57) **CLAIM**

We claim the ornamental design for a calibrator for wafer handling robots, as shown and described.

DESCRIPTION

FIG. 1 is a front, top and right side perspective view of a calibrator for wafer handling robots showing our new design;

FIG. 2 is a front elevational view thereof;

FIG. 3 is a rear elevational view thereof;

FIG. 4 is a right side elevational view thereof;

FIG. 5 is a left side elevational view thereof;

FIG. 6 is a top plan view thereof;

FIG. 7 is a bottom plan view thereof;

FIG. 8 is a cross-sectional view take along line 8-8 in FIG. 2; and,

FIG. 9 is a cross-sectional view take along line 9-9 in FIG. 2.

1 Claim, 9 Drawing Sheets

FIG. 2

FIG. 3

FIG. 4

FIG. 5

FIG. 6

FIG. 7

FIG. 8

FIG. 9
